Primary Examiner—Jennifer Rivard(74) *Attorney, Agent, or Firm*—Dykema Gossett PLLC;
Gregory M. Zinkl(57) **CLAIM**

The ornamental design for a smoking device, as shown and described.

DESCRIPTION

FIG. 1 is a perspective view of a smoking device showing my new design.

FIG. 2 is an isometric view of the smoking device shown in FIG. 1.

FIG. 3 is a side elevational view of the smoking device shown in FIG. 1.

FIG. 4 is a top plan view of the smoking device shown in FIG. 1.

FIG. 5 is a front elevational view of the smoking device shown in FIG. 1.

FIG. 6 is a back elevational view of the smoking device shown in FIG. 1; and,

FIG. 7 is a bottom plan view of the smoking device shown in FIG. 1.

The broken lines are shown for illustrative purposes only and form no part of the claimed design.
